UNITED STATES PATENT OFFICE.

HENRY S. HORNBECK, OF ELIZABETH, NEW JERSEY, ASSIGNOR TO VOLOTONE COMPANY, OF ELIZABETH, NEW JERSEY, A CORPORATION OF NEW JERSEY.

AUTOMATIC PIANO-PLAYER.

1,168,396.

Specification of Letters Patent.

Patented Jan. 18, 1916.

Application filed February 14, 1913. Serial No. 748,342.

To all whom it may concern:

Be it known that I, HENRY S. HORNBECK, a citizen of the United States, residing in Elizabeth, Union county, State of New Jersey, have invented certain new and useful Improvements in Automatic Piano-Players, of which the following is a specification, reference being had to the accompanying drawings, which form a part hereof.

10 This invention has for its object to provide improved devices for producing thematic effects under the control of the music sheet, and especially for the production of such thematic effects in pneumatic players 15 under the control of side perforations of the music sheet, that is, of special perforations in the music sheet which are placed so as to produce the thematic effects automatically. One embodiment of the invention explained hereinafter is designed with especial 20 reference to its use with perforated music sheets in which the perforations for the thematic tones are cut slightly behind the perforations for the accompaniment tones while 25 the side perforations determine the operation of the improved thematic or solo devices.

Another embodiment of the invention, also explained hereinafter, is specially designed 30 for use with perforated music sheets in which the perforations for the thematic tones are not necessarily cut behind the perforations for accompaniment tones, but each thematic device is controlled by a separate 35 side perforation and itself controls a group of player pneumatics sufficiently small to permit proper thematic effects to be produced.

In both of the embodiments of the invention shown and described herein the fulcrum of the lever through which each player pneumatic acts upon the corresponding hammer or tone producing device is yielding and, for the production of accompaniment tones, more 45 or less of the energy of the striking pneumatic is absorbed by the spring which yieldingly supports the fulcrum, while, to produce thematic effects, the fulcrum is prevented from yielding and the entire energy 50 of the striking pneumatic is transmitted to the tone producing device. The provision of a yielding fulcrum for the lever through which more or less of the energy of the striking pneumatic is transmitted to the tone producing device forms the basis of another ap-

plication in which the devices for preventing or limiting the yield of the fulcrum are shown as manually controlled. The provision of a yielding fulcrum is therefore not broadly claimed in the present case, but 60 rather, so far as the yielding fulcrum is concerned, the combination of the yielding fulcrum with devices whereby the yielding of the fulcrum is prevented or controlled automatically from the music sheet. 65

The invention will be more fully explained hereinafter with reference to the accompanying drawings in which it is illustrated and in which—

Figure 1 is a view in sectional elevation of so much of an automatic piano playing mechanism as is necessary to enable the invention to be understood, the thematic devices being designed with especial reference to their use in connection with music sheets 70 which have not only side perforations for control of the thematic devices but thematic perforations cut slightly behind the accompaniment perforations. Fig. 2 is a view of the same in front elevation. Fig. 3 is a 75 view similar to Fig. 2 but showing the thematic devices designed for use in connection with music sheets which have side perforations for the control of the thematic devices but have not the thematic perforations cut 80 in advance of the accompaniment perforations. Fig. 4 is a detail view in sectional elevation of the embodiment of the invention shown in Fig. 3. Figs. 5 and 6 are detail 85 views in sectional and front elevation respectively of a portion of the solo devices shown in Figs. 1 and 2. Figs. 7 and 8 are detail views illustrating particularly the devices by which the crescendo lever is also 90 enabled to control the production of a sforzando in any position. 95

Referring first to the embodiment of the invention shown in Figs. 1, 2, 5, 6, 7 and 8, each hammer *a*, arranged in suitable proximity to the corresponding piano string *a'*, is actuated through the usual action parts indicated at *a*² from the usual abstract *a*³. The latter is shown as having a lug *a*⁴ which rests upon the lever *b*³ through which the action of the player pneumatic is transmitted to the abstract and thence to the hammer or tone producing device. The lever *b* is fulcrumed as at *b*¹ and is connected by a link or rod *b*² with the corresponding player pneumatic *c* which in turn is con- 100
105
110

trolled, through the usual primary or controlling valve indicated at e' and the air duct c^2 , from the usual tracker board d and the perforated music sheet e . The 5 fulcrum b' of the lever b is yieldingly supported and is shown, in this instance, as carried by a lever f which has a fixed fulcrum f' at one end and at the other end is yieldingly supported by a suitable spring 10 f^2 . Obviously, if the fulcrum b' of the lever b is permitted to yield without restraint, except that of the spring f^2 , the energy of the striking pneumatic will be largely absorbed by the spring f^2 and the hammer a 15 will be actuated with a minimum of force, so that a very soft tone will be produced. It will also be obvious that if the yielding of the fulcrum of the lever b is prevented altogether or is limited more or less the 20 energy of the striking pneumatic will be communicated in whole or in part to the hammer or tone producing device and the tone produced will be loud or moderated more or less as the case may be. For ordinary crescendo effects, in which the dynamic force of all tones which may be produced is increased or diminished at will, the yielding of the fulcra of all of the levers f may be limited more or less by the crescendo bar 25 g which is carried by arms g' from a rock shaft g^2 . A controlling lever g^3 is connected to the rock shaft so that by hand the position of the crescendo bar g may be varied to limit more or less the movement 30 of the lever f and therefore the yielding of all of the fulcra b' , thereby modifying more or less the force of the blows struck by the hammers a .

For the production of solo or thematic 40 effects the music sheet e is cut with accompaniment perforations e' , with solo perforations e^2 slightly behind the accompaniment perforations, and with side perforations e^3 which determine the operation of 45 the solo or thematic devices, the said perforations e^3 being cut slightly behind the accompaniment perforations e' but slightly in advance of the solo perforations e^2 . The solo and accompaniment perforations control the action of the player pneumatics or 50 striking pneumatics e through the air ducts c^2 as usual. Each side perforation, in the construction now under consideration, controls means which prevent the yielding of 55 the fulcra of the transmitting levers b of the upper half of the scale or the lower half of the scale, as the case may be. In the arrangement shown each side perforation e^3 controls, through an air duct h and a primary or valve h' , a pneumatic i which actuates the solo stop hereinafter referred to. For this purpose an arm i' secured to the movable member of the pneumatic i is connected by a link i^2 with an arm i^3 which is 60 secured to the solo stop k , so that when the 65

pneumatic i is collapsed, under the control of the corresponding side perforations e^3 , the solo stop k , which normally stands clear of the path of movement of the levers f , is moved into such path of movement so as to 70 prevent the movement and therefore to prevent the yielding of the fulcra of the levers b . The solo stop is held in its normal position by the tension of the usual spring of the pneumatic i and is shown (see particularly Figs. 5 and 6) as hinged, as at k' , to a board or bracket m which is suitably supported. Obviously it may happen that the solo stop is moved from its normal position while some of the levers f are depressed and 75 in order that the proper movement of the solo stop may not be prevented under such circumstances, the solo stop is composed of a bar k^2 , to which the arm i^3 may be secured, and a series of felt blocks k^3 , one for each 80 lever f . Each block k^3 is hinged upon a bar k^2 as shown at k^4 , but oppositely with respect to the hinging of the bar k^2 , and is held yieldingly in its normal position by a flat spring k^5 . It will be seen that if the solo stop is moved toward the levers f when 85 any of the levers is depressed, the corresponding block k^3 will yield so as to permit the full movement of the solo stop to be accomplished and all other blocks k^3 to be placed in the path of the corresponding levers f . As soon as the levers f which have 90 been depressed are released the corresponding blocks k^3 will also swing forward under the ends of such levers as have been depressed and released.

It will now be seen that all accompaniment tones, being produced slightly in advance of solo tones, even of the same chord, are produced with a more or less moderated force, in dependence upon the position of the crescendo bar g , and that the solo tones in one half of the scale or in the other half, as determined by the side perforations e^3 , which uncover the ducts in the tracker board before the action of the devices which produce the solo tones is begun, are produced with the full force determined by the tension of the air in the player pneumatics of that half of the scale, for the levers f which correspond to the solo perforations will be locked against yielding by the corresponding solo lock, the operation of which is initiated by the corresponding side perforation. 105

The crescendo handle g^3 may be utilized, as shown in Figs. 1, 2, 7 and 8, for the production of a sforzando in whatever position the crescendo lever happens to be. For this purpose the crescendo lever or handle 110 is pivotally connected to the rock shaft g^2 , as shown at g^4 in Figs. 7 and 8, and is arranged to bear against a spring pressed bar g^5 which is connected by guide rods g^6 with a bar g^7 . The latter carries a valve g^8 which 115

normally covers the ports g^9 of ducts g^{10} . The ducts g^{10} are connected with the ducts h which connect the valves h' with the ports of the tracker bar which correspond to the side perforations e^3 , so that by a lateral movement of the handle g^3 both pneumatics i can be collapsed at once and both solo stops thus placed in the path of movement of the levers f of both halves of the scale, thereby producing a sforzando.

The embodiment of the invention shown in Figs. 3 and 4 is designed for use with a music sheet e in which the solo perforations e^5 are cut to the same line with the accompaniment perforations e^4 and the side perforations e^6 are cut slightly in advance of the line. The tracker board d , in this embodiment of the invention, is provided at each end with a series of ports d' each of which is connected, by a corresponding air duct h^2 , through a corresponding valve h^3 with a pneumatic i^4 which controls a small group of levers f which as before, are supported by springs f^2 and carry the fulcra b' of the transmitting levers b through which the player pneumatics c actuate the tone producing devices. Each group of levers f controlled by the corresponding pneumatic is so small that proper thematic effects can be produced by the operation of one or another of the pneumatics i^4 . Each pneumatic i^4 controls, substantially in the same manner as before, a corresponding solo stop h which may be constructed and arranged as already described. In this embodiment of the invention, the operation of which will be understood without further explanation, the thematic effects are produced wholly by the side perforations without regard to the cutting of the solo perforations in the music sheet and wholly under the control of the side perforations which must be specially cut.

Other embodiments of the invention will readily suggest themselves and it will be understood that the details of construction herein shown and described may be varied more or less to suit different styles of players and different requirements of use without departing from the spirit of the invention.

I claim as my invention:—

1. In a musical instrument, the combination of a series of playing devices having each a lever with a movable fulcrum adapted to yield bodily during the playing movement, and a series of automatic devices for limiting each the yielding of a portion of such fulcra.
2. In a musical instrument, the combination of a series of playing devices having each a lever with a yielding, spring suspended fulcrum, and a series of automatic devices for limiting each the yielding of a portion of such fulcra.

3. In a musical instrument, the combination of a series of playing devices having each a yielding fulcrum, automatic devices for controlling the movement of the yielding fulcra, and independent manually operated devices for limiting in different degrees the yielding of the fulcra when they are permitted by the automatic devices to yield.

4. In a pneumatic piano player, the combination of a playing mechanism including a series of levers having each a bodily movable fulcrum, a series of devices for limiting each the movement of a portion of the fulcra, and a series of automatically controlled pneumatics for actuating said devices severally.

5. In a pneumatic piano player, the combination of a playing mechanism including a series of levers and spring suspended fulcra therefor, adapted to yield bodily during the playing movement, a series of devices for limiting each the yielding of a portion of the fulcra, and a series of automatically controlled pneumatics for actuating said devices severally.

6. In a pneumatic piano player, the combination of a series of playing devices having each a lever with a yielding fulcrum, devices for controlling the movements of the several yielding fulcra, an automatically controlled pneumatic for actuating said devices, and independent, manually operated means for limiting in different degrees the yielding of all of the several fulcra when they are permitted by said last named devices to yield.

7. In a pneumatic piano player, the combination of a series of playing devices, having each a lever with a yielding fulcrum, devices for limiting the yielding of the several fulcra, a pneumatic for actuating said devices, a valve for controlling said pneumatic, independent means for limiting in different degrees the movement of the several fulcra, and a common handle operatively disposed with respect to said last named means and said valve and movable in different directions for controlling the same.

8. In a pneumatic piano player, the combination of tone producing devices, player pneumatics, transmitting means between the player pneumatics and the tone producing devices including each a lever and a spring suspended fulcrum therefor, a movable stop to control the yielding fulcra, a pneumatic to control the position of said stop, and a tracker board having ports and connections to said player pneumatics and a port and connection to said last named pneumatic.

9. In a pneumatic piano player, the combination of tone producing devices, player pneumatics, transmitting means between the player pneumatics and the tone producing devices including each a lever and a spring

suspended fulcrum therefor, a movable stop to control the yielding fulcra, a pneumatic to control the position of said stop, a tracker board having ports and connections to said player pneumatics and a port and connection to said last named pneumatic, and independent, manually controlled means for limiting in different degrees the move-

ment of said fulcra when they are permitted by said stop to yield.

This specification signed and witnessed this eighth day of February, A. D. 1913.
